UNITED STATES PATENT OFFICE.

THEODORE JONAS, OF REPUBLIC, MISSOURI.

BUILDING-WALL CONSTRUCTION.

No. 857,628.

Specification of Letters Patent.

Patented June 25, 1907.

Application filed October 12, 1905. Serial No. 282,465.

To all whom it may concern:

Be it known that I, THEODORE JONAS, a citizen of the United States, residing at Republic, in the county of Greene and State of Missouri, have invented certain new and useful Improvements in Building-Wall Constructions, of which the following is a specification.

This invention involves novel building wall construction, the essential features of the invention residing in the provision of construction of this type intended to resist to the greatest possible degree the penetration of dampness, frost or the like and at the same time the invention is designed to secure a comparatively cheap structure for the purposes desired.

The invention also involves a peculiar form of bond-block, the construction and advantages of which will appear fully in the appended description.

For a full description of the invention and the merits thereof and also to acquire a knowledge of the details of construction of the means for effecting the result, reference is to be had to the following description and accompanying drawings, in which:

Figure 1 is a plan view showing a building wall structure in accordance with the invention. Fig. 2 is a detail perspective view of one of the bond-blocks.

Corresponding and like parts are referred to in the following description and indicated in all the views of the drawings by the same reference characters.

The invention utilizes the principle of the air space in the building wall by which the non-penetrable qualities thereof are greatly subserved. In carrying out the invention and referring to the drawings, the characters A and B designate spaced tiers of building blocks 1, said tiers being connected by means of a bond-block 2 of peculiar form. The spaced relation of the tiers A and B of blocks 1 provides the air spaces 3 between said tiers and this air space will necessarily obviate likelihood of penetration of dampness, frost or the like to a great degree as has been noted in the practical use of wall construction of this type. Opposite end portions of adjacent blocks 1 of each tier A and B are formed with seats or recesses 4 so as to receive interlocking heads 5 which project from opposite sides of the bond-blocks 2. It is preferred that the recesses or seats 4 of the blocks 1 be of angular contour or many sided, and the

heads 5 of the bond-blocks are designed to snugly fit in pairs of adjacent seats 4 to interlock therewith. In the construction shown, the heads 5 are of somewhat dove-tail form 60 and the seats 4 so receive the heads of the bond-blocks as to establish a positive interlocking connection between the blocks 1 of each tier A and B in the manner which will be readily seen. The bodies of the blocks 2 65 are arranged between the tiers of blocks 1 and space the tiers apart accurately to form the air space 3.

The blocks 2 may be of a length, vertically speaking, equal to the thickness of one or more of the tiers of superposed blocks 1 as is brought out more clearly in the modification in Fig. 3, but it will be understood that this feature is nonessential in the broad contemplation of the invention. The seats 4 of the blocks 1 extend from the inner sides of the blocks and terminate some distance from the outer sides so that adjacent ends of the several blocks 1 of each tier A and B are in contact as indicated at 6.

It will be observed that opposite ends of the body portion of the block 2 project beyond the sides of the extensions or heads 5, or in other words, the block is longer than the diametrical extent of the heads 5 at 85 the points of jointure of the latter with the body of the block. The above construction forms shoulders 2^b at opposite ends of the block 2, projecting from opposite sides of each of the heads 5, and these shoulders abut 90 with the inner sides of the blocks 1 of the spaced tiers A and B. The formation of the shoulders 2^b not only increases the resisting quality of the blocks 2, so far as regards inward pressure on the tiers A and B, but when 95 the blocks 2 are in position and mortared to the tiers A and B, the shouldered portions 2^b increase the bonding action of the blocks in an obvious way.

In the construction before described, the blocks 1 may be made of plastic material of a suitable nature and molded in a manner similar to the manner of forming the majority of building blocks now in use.

It is to be noted that each building block 1 105 is provided at its inner side only with a single dove-tailed tenon 10 the angular faces of which coincide with and constitute a portion of the end boundaries of the block, the remaining portion 6 of said end boundaries extending perpendicular to the outer side of the block. It will be seen also that each bond

block 5 is composed of a body portion providing at each end two rectangular shoulders and a dove tailed head at each side of its body portion, each of said heads being formed with four walls, namely two diverging walls adjoining the body portion and two converging walls joining the diverging walls at an angle and meeting at the perpendicular abutting portions 6 of the building blocks. 10 Hence by this arrangement it is not necessary, in building a wall, to fit any block into its mating block with a downward movement, to effect the binding action, but taking Fig. 1 for instance it will be seen that the first bond 15 block to the left may be slid sidewise into the two building blocks at the extreme left that are shown broken away, then the next two building blocks fitted in with a sidewise or sliding movement against the opposite side of 20 the bond block and so on around the wall. This has an advantage, obviously, and is accomplished by the precise arrangement shown and set forth in the appended claim.

Having thus described the invention, what 25 is claimed as new is:

In wall construction, the combination of inner and outer walls spaced apart, each wall

being of like structure and composed of blocks laid in courses, the vertical joints between opposing blocks alining transversely, 30 each block having a terminal abutting surface at its outer corner and a V-shaped recess at its inner corner, whereby adjacent blocks butt at their outer corners and have mortises formed between their ends at the inner corners, said mortises having their walls outwardly diverged for a part of their length, thence inwardly converged for the remainder of their length, and spacing bond blocks tying the walls and spaced apart and having opposite lateral extensions to come between the wall blocks, and end tenons fitted in the aforesaid mortises, said tenons having their walls outwardly diverged, thence inwardly converged, the said bond blocks breaking 35 joint with the wall blocks, the wall blocks and the spacing bond blocks being laid in courses in the formation of the wall.

In testimony whereof I affix my signature in presence of two witnesses.

THEODORE JONAS. [L. S.]
